UNITED STATES PATENT OFFICE.

A. THEODORE JOHN, OF NEW YORK, N. Y.

THUMB-BRACE FOR VIOLIN-PLAYERS.

SPECIFICATION forming part of Letters Patent No. 389,085, dated September 4, 1888.

Application filed April 21, 1888. Serial No. 271,442. (No model.)

To all whom it may concern:

Be it known that I, A. THEODORE JOHN, of the city, county, and State of New York, have invented certain new and useful Improvements 5 in Thumb-Braces for Violin-Players, of which the following is a specification.

In learning to play the violin it is necessary to hold the bow in such a manner that the latter can be firmly yet easily passed over the 10 strings. This is accomplished by the free motion of the wrist in connection with the proper holding of the end of the bow by the fingers. To secure the proper hold of the bow, the thumb has to form an angle at the first joint, 15 as thereby only the free and easy motion of the wrist can be obtained. To hold the thumb in proper position, especially to learners, is connected with some difficulty, as they are apt to hold the bow with straight or inwardly-bent 20 thumb, which, however, impedes the free motion of the wrist and prevents the production of a full tone.

My invention is designed to furnish a cheap and simple device by which the proper position of the thumb can be easily acquired by 25 learners, and thereby the proper holding and leading of the bow be acquired without difficulty and with less trouble to the teacher; and the invention consists of a thumb-brace for 30 violin-players, which is composed of a rigid angular brace, an elastic band attached to one side of said brace and passed around the thumb, and means for fastening the other end of the 35 band to the brace, as will be fully described hereinafter, and finally be pointed out in the claims.

In the accompanying drawings, Figure 1 represents a perspective view of my improved thumb-brace for violin-players, shown in position for use, the hand and bow being shown 40 in dotted lines; and Figs. 2 and 3 are respectively a detail end view and a side view of the thumb-brace.

Similar letters of reference indicate corresponding parts.

In the drawings, A represents an angular body of a thumb-brace, which body is made of

sheet metal, hard rubber, or other rigid material, and transversely curved in such a manner as to fit the outer contour of the thumb at 50 the first joint, so that the same is held at the proper angle for holding the violin-bow. To a slot, a, at one side of the shank of the brace is applied one end of an elastic band, B, the other side of which is provided with a hook, 55 C, that engages a slot or eye, b, at the opposite side of the shank, so as to attach the hook to the body of the brace. Any suitable means by which the band B is attached to the shank of the brace A may be used. The brace A is 60 placed on the thumb, as shown in the drawings, and the band passed around the same and attached by the hook to the shank of the brace and held firmly in position on the thumb. The brace A forms a support for the thumb 65 and accustoms the same to the bent position required in playing the violin. It prevents the straightening out of the thumb, and obviates thereby in an effective manner the possibility of holding the bow with straightened or 70 inwardly-bent thumb. The brace facilitates the labors of the teacher as well as of the learner, and forms a cheap and simple device for securing the proper position of the thumb in holding the bow.

Having thus described my invention, I claim as new and desire to secure by Letters Patent—
1. A thumb-brace for violin-players, composed of an angular transversely-curved body and an elastic band applied to the shank of 80 said brace, substantially as set forth.

2. A thumb brace for violin-players, composed of an angular transversely-curved body, an elastic band attached at one end to the shank of said brace, and a hook attached to the other 85 end of the band and adapted to engage a slot or eye of the shank, substantially as set forth.

In testimony that I claim the foregoing as my invention I have signed my name in presence of two subscribing witnesses.

A. THEODORE JOHN.
